UNITED STATES PATENT OFFICE.

MAX RACHLIN, OF NEW YORK, N. Y.

GUTTER HANGER.

Application filed March 22, 1923. Serial No. 626,827.

To all whom it may concern:

Be it known that I, MAX RACHLIN, a citizen of Russia, and resident of the city of New York, in the county of Kings and State 5 of New York, have invented certain new and useful Improvements in Gutter Hangers, of which the following is a specification.

The present invention relates to improvements in gutter-hangers, that is to say to devices for supporting roof gutters.

The main object of the invention is to provide a gutter-hanger, including a bar extending transversely of the gutter and provided on one of its ends with a hook-shaped 15 section fitting over the bead of the gutter, a simple and efficient means being provided for effectively locking the said hook-shaped section in position.

Another object of the invention is to provide a gutter-hanger of the type mentioned which is simple in construction, efficient in operation, durable in use and capable of manufacture on a commercial scale, or in other words one which is not so difficult to 25 make as to be beyond the reasonable cost of such a contrivance.

With these and other objects in view, which will more fully appear as the nature of the invention is better understood, the 30 same consists in the combination, arrangement and construction of parts hereinafter described, pointed out in the appended claims and illustrated in the accompanying drawings, it being understood that many 35 changes may be made in the size and proportion of the several parts and details of construction within the scope of the appended claims, without departing from the spirit or sacrificing any of the advantages 40 of the invention.

A few of the many possible embodiments of the invention are illustrated in the accompanying drawings, in which:—

Figure 1 is a vertical section taken through 45 a gutter-hanger constructed in accordance with the present invention, the gutter being shown in position thereon; Fig. 2 is a section taken on line 2—2 of Fig. 1; Fig. 3 is a side elevation of the transversely extending bar of the gutter-hanger and portions 50 of the elements co-operating therewith; Fig. 4 is a section taken on line 4—4 of Fig. 3; Fig. 5 is a section taken on line 5—5 of Fig. 3; Fig. 6 is a perspective view of the inner 55 end of the transversely extending bar of the hanger; Fig. 7 is a section similar to the one

shown in Fig. 1 of a modification of the invention; Fig. 8 is a plan view of the blank of which the transversely extending bars of the hangers shown in Figs. 1 to 7, inclusive, 60 are made; Fig. 9 is a section similar to the one shown in Fig. 7 of a further modification of the invention; and Fig. 10 is a plan view of the hanger shown in Fig. 9 in flat condition.

Referring now first to Figs. 1 to 6, inclusive, of the drawings, the numeral 13 indicates a roof-gutter, the outer edge of which is provided with a bead 14, as usual in constructions of this type, while its inner edge 70 15 is plain. For supporting this gutter in proper relation to the roof 16 of the building, there is provided a plurality of hangers, spaced apart a suitable distance, each of 75 said hangers including a gutter embracing strap 17, a transversely extending bar 18, and a bracket 19, the latter being attached to said bar and roof. The bar and bracket are made of sheet metal of any preferred 80 gage and united by rivets or other suitable fastening means, while the embracing strap 17 is made of wire.

The bar 18 includes an outer hook-shaped section 20, fitting over the bead 14 of the gutter, its opposite end 21 being bent over 85 the plain edge of the gutter, as clearly shown in Fig. 1 of the drawings. The free end of the hook-shaped section 20 of the bar 18 is fork-shaped, as shown at 22 in Figs. 4 and 5 of the drawings, an aperture 23 extending through the hook-shaped section 20 centrally in rear of the prongs of the said 90 fork-shaped end, and through this aperture is extended the gutter-embracing wire 17. The outer end of the wire is flattened as 95 shown at 24, the flattened end being disposed between the prongs of the fork-shaped end of the hook-shaped section 20. The said fork-shaped end and the flattened end 24 of the wire strap 17 project into the 100 bead 14 of the gutter, for a purpose herein-after to be described, while the other end of the wire extends through an aperture 25 in the bent portion 21 of the bar 18, and is thence bent downwardly into contact with 105 the rear face of the said bent portion, as shown at 26. In the rear face of the bent portion 21 of the bar 18 is formed a groove 27, in which the downwardly bent end portion 26 of the wire 17 is disposed. The rear 110 face of the bent portion 21 of the bar 18 presents thus a flat surface when the wire is

therein. The inner end of the bar 18 is provided with inwardly projecting prongs 28, which are adapted to be driven into the inner plain edge 15 of the gutter, so as to securely hold the hanger on the gutter. The bracket 19 is joined with the bar 18 by a rivet 29, or otherwise, the bracket being secured by nails 15', or otherwise, to the roof 16, from which the rain water is to be carried off.

In use, the wire strap 17 is drawn through the aperture 23 in the hook-shaped section 20 of the bar 18, and the said hook-shaped end engaged with the bead 14 of the gutter, the fork-shaped end 22 of the said bar and the flattened portion 24 of the gutter embracing strap 17 being inserted into the said bead. The bent portion 21 of the bar 18 is then engaged with the plain edge 15 of the gutter. After this, the strap 17 is bent around the gutter and extended through the aperture 25 in the bar 18. The free inner end of the strap is then bent downwards into the groove 27, and the prongs 28 driven into the gutter. Finally, the bracket 19 is fastened to the roof. The outer end of the bar 18 and the flattened end of the strap 17 are engaged with the bead of the gutter in order to hold the hook-shaped section 20 of the bar 18 in contact with the bead throughout the length of the said hook.

The modification shown in Fig. 7 of the drawings differs from the one above described in that the gutter embracing straps 17 is missing. Otherwise the construction and operation of the elements are the same as of those described in connection with Figs. 1 to 6, inclusive, of the drawings.

A further modification of the invention is illustrated in Figs. 9 and 10 of the drawings, differing from the construction illustrated in Figs. 1 to 6, inclusive, in that the gutter embracing strap 30 consists of a flat strip of metal, which is gradually reduced in width from its outer end 31 to its inner end 32. The outer end is drawn through two transverse slots 33 in the transversely extending bar 18' and is extended into the bead of the gutter, the inner end of the said strip being drawn through a transverse slot 34 in the bent portion 21' of the bar 18', and then bent downwards onto the rear face of the said bent portion 21'. The bracket 19' is also made in the form of a flat strip of metal, the lower end 36 of which is drawn through transverse slots 36 in the bar 18'. Otherwise the construction and operation

of the elements are the same as of those described in connection with Figs. 1 to 6, inclusive, of the drawings. It is to be noted, however, that the free end of the hook-shaped section of the bar 18' is not disposed within the bead of the gutter.

The gutter embracing straps 17 and 30 are longitudinally shiftable on the transversely extending bars 18 and 18', respectively, and are also detachable therefrom. In arranging these straps shiftably on the bars, their hook-engaging ends may be extended into the beads of the gutter and the straps used as levers in bending the hook-shaped ends of the bars around the beads. When the bending operation has been finished, the gutter embracing straps are drawn out from the bead as far as the construction permits and then tightly bent against the underface of the gutter.

What I claim is:

1. A gutter-hanger comprising a bar extending transversely of the gutter and provided at its outer end with a hook-shaped section fitting over the bead of the gutter, the opposite end of said bar being fixed to the opposite edge of the gutter, and a strap member shiftable longitudinally upon the hook-shaped section of said bar tightly embracing the underface of the gutter and engageable with the opposite end of said bar, the outer end of said strap member being adapted for insertion within the beaded edge of the gutter to lock said hook-shaped section in position.

2. A gutter-hanger comprising a bar extending transversely of the gutter and provided at its outer end with a hook-shaped section fitting over the bead of the gutter, the opposite end of said bar being fixed to the opposite edge of the gutter, a strap member shiftable longitudinally on the hook-shaped section of said bar tightly embracing the underface of the gutter and engageable with the opposite end of said bar, the last mentioned end of said bar being provided in its rear face with a groove in which the inner end of said strap member is adapted to be seated, the outer end of said strap member being adapted for insertion within the beaded end of said gutter to lock said hook-shaped end in position.

Signed at New York, in the county of New York and State of New York, this 21st day of February, A. D. 1923.

MAX RACHLIN.
